UNITED STATES PATENT OFFICE

MICHEAL J. McSHANE, OF SEATTLE, WASHINGTON

RIGGER HOOK

Application filed January 16, 1930. Serial No. 421,239.

The present invention relates to hooks and more particularly to hooks adapted for use in hoisting apparatus or the like.

An object of this invention is to provide a safety hook which may be used in combination with conventional hoisting apparatus and which is so constructed that the article being hoisted will not slip off of the hook until the locking member is released.

Another object of this invention is to provide a hook of the character described wherein the ring member is provided with a predetermined amount of play or rotatability upon the hook so that when the article held thereby swings laterally of the hoisting apparatus the locking member will not readily be released.

A further object of this invention is to provide a hook of the character described which is readily and cheaply manufactured and which will be of sufficient strength to safely hold the desired load to be lifted.

The above and various other objects and advantages of this invention will in part be described in and in part be understood from the following detailed description of the present preferred embodiment, the same being illustrated in the accompanying drawing, wherein:

Figure 1 is a detail side elevation of a device constructed according to the preferred embodiment of this invention;

Figure 2 is a longitudinal section partly in detail taken substantially on the line 2—2 of Figure 1; and

Figure 3 is a detail top plan view of the link member.

Referring to the drawing wherein like numerals of reference designate corresponding parts throughout the several views, the numeral 10 designates generally a hook member which is provided with a bifurcated upper end portion 11.

The upper end portion 11 is provided with an aperture 12 therethrough for rockably re-

ceiving a ring member 13. A locking jaw or pawl member 14 is adapted to be loosely mounted in the bifurcated upper end portion 11 of the hook member 10.

The movable jaw member 14 is preferably provided with a substantially annular portion 15 which loosely engages within the bifurcated member 11. The annular member 15 is provided with an axial opening 16 for receiving the ring member 13 which is adapted to be loosely mounted therein.

The locking member 14 is preferably provided with a tapering or angularly inclined lower end portion 17 which is adapted to bear against the pointed or upwardly extending portion 18 of the hook 10 so that when the locking member 14 is swung inwardly the angular portion 17 of the locking member 14 will securely lock the desired element on the hook.

The outer face of the locking member 14 is preferably flush with the outer face of the hook 10 and the annular member 15 is preferably provided with an outstanding flange or segmental portion 19 which is adapted to loosely engage about the bifurcated rounded portion 20 of the upper end 11.

The locking member 14 is provided with an upstanding lug 21. A link member 22 is mounted on the ring 13 and is preferably constructed in two sections which may be held together by a bolt or securing member 23 or the like. The link member 22 may also be secured to the ring 13 by welding or the like in which case the securing member 23 may be eliminated.

If desired, the rear half of the link 22 may be constructed substantially straight and the forward half thereof be formed on an arc so that the lug or stud 21 will be loosely positioned therebetween. The ring 13 is preferably provided with a pair of collars 24 which are positioned upon the opposite sides of the bifurcated upper end portion 11 and are adapted to prevent the

ring 13 from lateral movement on the hook 10.

In the use of this device the hook member 10 may engage the desired hoisting cable or the like, the pawl or locking jaw member 14 being swung outwardly so as to permit the cable to be inserted in the hook.

The ring member 13 may be swing forwardly so that the link 22 will engage the lug 21 and thereby cause the locking member 14 to swing on its pivot and engage against the hook portion 18. It is obvious that the ring member 13 not only serves the purpose of providing an extended pivotal member for the movable jaw but also provides means by which the hook 10 may be hoisted or otherwise secured to conventional hoisting apparatus. The ring 13 during the assembly of the component parts of the hook will of course be split, but the open portions of the ring when the assembly has been completed will be assembled or otherwise secured together so as to provide a solid ring.

While the material is being hoisted it frequently occurs that the cable will be swung horizontally and through the provision of the link member 22 the ring 13 is given a predetermined amount of play before the link member 22 will engage the lug 21 so as to open the hook.

It will, therefore, be seen that a safety hook has been provided which will not open during the hoisting operation.

It is, of course, understood that various changes and modifications may be made in the details of construction and design of the above specifically described embodiment of the invention without departing from the spirit thereof, such changes and modifications being restricted only by the scope of the following claims:

What is claimed is—

1. A hook of the character described comprising a hook member, a movable jaw member secured to said hook, and a ring rockably carried by said hook, said ring also providing a pivotal member for said movable jaw.

2. A hook of the character described comprising a bifurcated hook member, a rockable jaw member carried by said hook, an upstanding lug mounted on said rockable jaw member, a ring rockably carried by said hook, and lug engaging means carried by said ring whereby to cooperatively move said jaw with the movement of said ring.

3. A hook of the character described comprising a hook portion, locking means rockably carried by said hook, a lug upstanding from said locking means, a ring rockably mounted on said hook, and link means secured to said ring and engaging said lug therebetween.

4. A hook of the character described comprising a hook member, a movable locking

member carried by said hook member, a lug upstanding from said movable locking member, a ring rockably mounted on said hook, a plurality of collars carried by said ring and engaging said hook, and a link member mounted on said ring and engaging said lug therebetween whereby to swing said movable locking member cooperatively with the swinging of said ring.

In testimony whereof I hereunto affix my signature.
